UNITED STATES PATENT OFFICE.

ANNE E. TABOR, OF DETROIT, MICHIGAN.

WEARING-APPAREL.

SPECIFICATION forming part of Letters Patent No. 742,928, dated November 3, 1903.

Application filed June 26, 1903. Serial No. 163,039. (No model.)

To all whom it may concern:

Be it known that I, ANNE E. TABOR, a citizen of the United States, residing at Detroit, in the county of Wayne and State of Michigan, have 5 invented certain new and useful Improvements in Wearing-Apparel, of which the following is a specification, reference being had therein to the accompanying drawings.

The invention relates particularly to ladies' 10 waists; and the objects of my improvement are to provide a waist that will readily adjust itself to all positions of the body, that will fit the body as tightly as may be desired and yet not interfere with the breathing, and that will 15 act as a support for other wearing-apparel.

The invention consists in the novel and simple construction of the waist, as will be described in the following specification and more particularly pointed out in the claim. 20 In the accompanying drawings, Figure 1 is a front view, and Fig. 2 is a rear view, of my improved waist, and Fig. 3 is a view of the front sections.

Heretofore in the construction of waists of 25 the character described it has been the usual practice to form the garment of two like sections, with a lacing at the back to permit of adjustment of the sections to fit the figure. This style of garment, however, has been 30 found unsatisfactory in use, as in adjusting the parts to enlarge the waist the shoulder-straps are necessarily separated and tend after the adjustment has been effected to slip 35 from the shoulders. It is also objectionable, as it forms, in effect, a corset, confining the breathing to the upper part of the chest and preventing the proper expansion of the bust.

To overcome these objections, I have provided 40 a construction having all the advantages of a rigid inelastic corset and the conveniences of a loose waist. This I have accomplished by making the waist in three parts—an inelastic back section A, to which the shoulder-straps B and C are secured, and two like front 45 sections B' and C', joined to the back section at the side of the garment by laces D. These laces in turn are preferably made elastic, so that they will expand and contract in breathing, thus holding the waist snugly, but not 50 too tightly, to the figure, thereby permitting

no part to wrinkle and insuring a perfect fit of the outer garment. The complementary front sections have their meeting portions detachably connected by any suitable means. In this instance I have shown a series of buttons D' as constituting the fasteners. 55

By forming the garment in the manner set forth it will be obvious that the front sections may be adjusted by the laces either to increase or diminish the waist size without in 60 any manner affecting the position of the straps.

Each section B' and C' is provided at its lower edge with an inelastic band or belt F and at its upper edge with a similar band or 65 inelastic portion G. To this latter band the free ends of the straps B and C are attached, being preferably adjustably connected thereto by any suitable devices—as, for instance, the pins a'. 70

The material of each front section intermediate the inelastic bands is gathered, commencing at a point b above the lower band, and is drawn together, as at a, where the material is joined to the upper band. This excess of material is, as shown, arranged in 75 folds, so that the waist will fit the figure properly, and while the material itself is inelastic the gathered portions described are yielding, permitting the proper expansion of the bust 80 for breathing and at the same time serving as a satisfactory support therefor.

A series of buttons f may be placed upon the lower inelastic bands of the front sections and upon the lower edge of the back section, 85 to which the skirts or other wearing-apparel may be secured.

Having now described my improved construction, what I claim as my invention, and desire to secure by Letters Patent, is— 90

In a waist, an inelastic back section A having a transverse band at its lower edge and shoulder-straps fixed thereto at its upper edge, a pair of inelastic front sections having transverse bands F at their bottom edges and transverse pieces at their upper edges for attachment to the free ends of the shoulder-straps, means for detachably securing the meeting edges of the front sections together, elastic connecting means between the back section 95 and the front sections, and elastic connecting means between the front sections 100

and the adjoining edges of the front sections, devices for supporting garments from the transverse bands of the back and front sections, and fulled breast portions in the front 5 sections, said fulled portions being largest at points adjacent to the transverse pieces at the top of the front sections and gradually merging downwardly to the transverse bands

at the bottoms thereof and to the side edges of the same.

In testimony whereof I affix my signature in presence of two witnesses.

ANNE E. TABOR.
